US0D1081570S

(12) **United States Design Patent** (10) **Patent No.:** **US D1,081,570 S**
(45) **Date of Patent:** ** *Jul. 1, 2025

(54) **PORTABLE POWER SUPPLY**

(71) Applicant: **SHENZHEN IMDK MEDICAL TECHNOLOGY CO., LTD**, Shenzhen (CN)

(72) Inventor: **Changchun Xia**, Wenzhou (CN)

(73) Assignee: **SHENZHEN IMDK MEDICAL TECHNOLOGY CO., LTD**, Shenzhen (CN)

(*) Notice: This patent is subject to a terminal disclaimer.

(**) Term: **15 Years**

(21) Appl. No.: **35/516,312**

(22) Filed: **Jan. 31, 2023**

(80) **Hague Agreement Data**

Int. Filing Date: **Jan. 31, 2023**

Int. Reg. No.: **DM/226546**

Int. Reg. Date: **Jan. 31, 2023**

Int. Reg. Pub. Date: **Feb. 17, 2023**

(30) **Foreign Application Priority Data**

Dec. 14, 2022 (CN) 202230838506.5

(51) **LOC (15) Cl.** **13-02**

(52) **U.S. Cl.**

USPC **D13/110**

(57) **CLAIM**

The ornamental design for portable power supply as shown and described.

DESCRIPTION

1. Portable power supply

1.1 : Perspective

1.2 : Front

1.3 : Back

1.4 : Left

1.5 : Right

1.6 : Top

1.7 : Bottom

1.8 : Perspective

Fig. 1.1 is a top, front, right side perspective view of a portable power supply, showing the claimed design; fig. 1.2 is a front elevation view thereof; fig. 1.3 is a back elevation view thereof; fig. 1.4 is a left side elevation view thereof; fig. 1.5 is a right side elevation view thereof; fig. 1.6 is a top plan

(Continued)

view thereof; fig. 1.7 is a bottom plan view thereof; and fig. 1.8 is a top, rear, left side perspective view thereof.
